UNITED STATES PATENT OFFICE.

JAMES G. BLUNT, OF SCHENECTADY, NEW YORK.

ARTICULATED LOCOMOTIVE.

Application filed November 22, 1927. Serial No. 234,950.

This invention relates generally to locomotives of the articulated type, and its object is to provide means for supporting the front end of the boiler on the front main frame, with the capability of swivelling and lateral movements of the main frame, relatively to the boiler, which means, while imposing a low yielding resistance to such relatively lateral movement, when the locomotive is traversing curved track, will positively centre the main frame, by gravity, when the locomotive is traversing tangent track.

The invention is particularly adapted for application in exceptionally heavy locomotives, where the load imposed on the boiler bearings is so great that the ordinary type of spring operated centering device cannot efficiently overcome the friction between the sliding members.

20 The improvement claimed is hereinafter fully set forth.

In the accompanying drawings: Figure 1 is a side view, in elevation, of a locomotive embodying the invention; Fig. 2, a partial plan view of the same, with the boiler removed, showing the relative positions of the front and rear frames, and of the centering device, when the locomotive is traversing curved track; Fig. 3, a side view, in elevation, 25 of the centering mechanism; Fig. 4, a vertical section of the same, taken at the centre of the frame; Fig. 5, a front end view, in elevation, of the mechanism; Fig. 6, a vertical transverse section, taken at the centre of the mechanism; Fig. 7, a plan view of the geared roller guide; Fig. 8, a plan view of the mechanism, the boiler bearing saddle being shown in section, taken on the line A A of Fig. 4; and, Fig. 9, a plan view of the same, with the 30 upper roller seats and the roller guide removed.

In the practice of the invention, referring descriptively to the specific embodiment thereof which is herein exemplified, as applied to a four cylinder articulated locomotive, the rear frame, 10, is pivotally connected to the front frame, 11, by the hinge pin, 12. The boiler, 13, is rigidly mounted on the rear frame, and supported on the front frame, by mechanism permitting swivelling and lateral movements of the front frame, relatively to the rear frame and the front of the boiler.

The lateral motion mechanism comprises 55 a bed plate, 14, which is fastened to the transverse frame brace, 15, and the brake hanger

brackets, 16. Four lower roller seats, 17, are mounted on the bed plate, each seat being provided with depending flanges, 18, which overlap the bed plate, to prevent longitudinal movement of the seats. Each roller seat is formed centrally with a rack, 19, which is inclined upwardly, on both sides of the central vertical plane of the seat. Similarly formed upper roller seats, 20, are mounted 60 on a boiler bearing yoke, 21. Interposed between the members of each pair of upper and lower roller seats, is a roller, 22, having gear teeth which mesh with the racks of the seats. Each roller is rotatively mounted on a pin, 70 23, and the pins are mounted in a frame or guide, 24. One end of each pin is made square to fit a correspondingly shaped socket in the side walls of the guide. Cotter pins, 25, serve to lock the pins, 23, in place. The roller guide 75 serves to maintain the rollers in fixed spaced relation, and flanges, 26, formed on the side walls of the guide, and extending along the sides of the roller seats, serve to hold the rollers on the seats. Each roller seat is made 80 independent of the others, to permit the seats to be properly adjusted to suit the centres of the rollers. When the proper adjustment of the seats has been made, the seats are secured 85 in place by dowel pins, 27, and suitable welding about their edges. The described construction permits the necessary lateral movement of the front frame, relatively to the boiler, to accommodate the locomotive to curved track, and ensures the return of the 90 frame, by gravity, to normal central position on tangent track.

To provide for the necessary swivelling movement of the front frame, the boiler bearing saddle, 28, is mounted on a plurality of 95 aligned cylindrical rollers, 29, which are superposed on the bearing yoke, 21. The boiler bearing yoke is substantially of cross shape, and is provided with four thrust blocks, two of which, 30, are disposed dia- 100 metrically opposite one another, in the longitudinal central plane of the front frame, and two of which, 30a, are similarly disposed in a transverse plane of the frame. The thrust blocks are fitted in suitable channels in the 105 boiler bearing yoke, 21, and have thrust bearing surfaces, formed concentric with the centre of the yoke. The thrust blocks, 30a, rest on the wear surface, 31, of the bearing yoke, and are clamped in place by the rec- 110 tangular cover plates, 32, which also serve as guides for the long arms of a swivel yoke,

33. The thrust blocks, 30, are clamped in place in their channels, by the upper and lower plates, 32^a, which also serve as guides for the short arms of the swivel yoke.
- 5 34. The swivel yoke, 33, is cross shape, having two long arms, 33^a, and two short arms, 33^b. Each of the arms terminate in a thrust bearing surface, having a curvature to match the opposed thrust block.
- 10 35. The swivel yoke is formed open at the centre, for the reception of the guide, 34, for the rollers, 29, which are rotatively mounted on pins, 35, rotatively mounted in the guide. The rollers, 29, are each composed of a plurality of narrow cylinders, to prevent undesirable slippage, as the outer ends of the rollers must travel farther than the inner ends, when swivelling movement occurs. To ensure the same distance of travel of the rollers, 20 on the bearing surface of the boiler bearing yoke and the wear plate, 36, of the boiler saddle, a geared pinion, 37, is mounted on the outer end of each of the pins, 35. Each pinion meshes with a lower rack, 38, having a 25 rectangular base, which is fitted into a similarly shaped opening in the boiler bearing yoke; and an upper rack, 39, formed with a cylindrical extension, which fits into an enlarged opening in the boiler saddle. After 30 the racks have been suitably adjusted, to suit the pinions, they are welded in position. The teeth of the pinion and of the racks are developed so that the pinion may revolve like a cone about its vertex, which, in the construction shown, is a point midway between the two rollers, on the axial lines of the 35 pins, 35.
36. The top roller guide is provided, at its centre, with a rectangular opening, 40, in 40 which is slidably fitted the crosshead, 41. The crosshead is free to revolve about a pin, 42, the lower end of which is made square, and fitted in a similarly shaped opening in the boiler bearing yoke. A nut, 43, threaded 45 on the lower end of the pin, serves to secure it to the bearing yoke.
37. The boiler bearing saddle is connected to the swivel yoke, by two depending box shape extensions, 44, which fit, with the capability 50 of longitudinal movement, in rectangular shaped openings, 45, formed in the swivel yoke. The lower ends of the extensions project below the boiler bearing yoke, and stops, 46, in the form of narrow cylinders, are bolted 55 thereto, after the parts are assembled. The cylinders serve as stops, to prevent abnormal separation of the bearing yoke and the saddle, thus ensuring the maintenance of the pinions and racks in mesh.
- 60 38. To prevent the geared rollers from unmeshing from their racks, and to limit transverse movement of the rollers, two safety yokes, 48, are provided. The yokes are bolted to the transverse frame brace, one in the 65 front and one in the rear of the boiler bear-

ing yoke, and each is formed with an opening, 49, the upper wall of which is provided with two upwardly and oppositely inclined bearing surfaces, 50. The boiler bearing yoke, 21, is provided, at its front and rear, with a downward extension, 51, having an end, 52, which projects through the opening, 49, in the yoke, and is adapted to bear on the inclined surfaces, 50, to prevent the separation of the upper and lower bearing seats for the geared rollers. The opening, 49, is made of a limited length, so that the extensions, 50, when unusual lateral stresses are encountered, will strike against its side walls, to prevent too great a degree of lateral movement of the 70 rollers.

The invention claimed as new and desired to be secured by Letters Patent is:

1. In a locomotive, the combination of a plurality of main frames, articulated together; a boiler, rigidly mounted on one of the frames, and extending over another; and means, on said second mentioned frame, for supporting the boiler, comprising means adapted to permit lateral movement of the 85 second mentioned frame, relatively to the boiler, when the locomotive is traversing curved track, and to return the second mentioned frame to normal central position, by gravity, when the locomotive passes from 90 curved to tangent track.

2. In a locomotive, the combination of a plurality of main frames, articulated together; a boiler, rigidly mounted on one of the frames, and extending over another; and means, on said second mentioned frame, for supporting the boiler, comprising a geared roller device adapted to permit lateral movement of the second mentioned frame, relatively to the boiler, when the locomotive is 100 traversing curved track, and to return the second mentioned frame to normal central position, when the locomotive passes from 105 curved to tangent track.

3. In a locomotive, the combination of a 110 plurality of main frames, articulated together; a boiler, rigidly mounted on one of the frames, and extending over another; and means, on said second mentioned frame, permitting swivelling movement of the second mentioned frame, relatively to the boiler, and means, adapted to permit lateral movement of said second mentioned frame, relatively to the boiler, when the locomotive is traversing 115 curved track, and to return the second mentioned frame to normal central position, by gravity, when the locomotive passes from 120 curved to tangent track.

4. In a locomotive, the combination of a 125 plurality of main frames, articulated together; a boiler, rigidly mounted on one of the frames, and extending over another; and means, on said second mentioned frame, for supporting the boiler, comprising means, per-

mitting swivelling movement of said second mentioned frame, relatively to the boiler, and means, embodying geared rollers adapted to permit lateral movement of the second mentioned frame relatively to the boiler when the locomotive is traversing curved track and to return the second mentioned frame to normal central position by gravity when the locomotive passes from curved to tangent track.

5. In a locomotive the combination of a plurality of main frames articulated together; a boiler rigidly mounted on one of the frames and extending over another; and means, on said second mentioned frame for supporting the boiler, comprising a plurality of geared rollers, each interposed between an upper and a lower roller seat, each seat embodying a rack, and each pair of seats being independent.

15. In a locomotive, the combination of a plurality of main frames, articulated together; a boiler, rigidly mounted on one of the frames, and extending over another; and means, on said second mentioned frame, for supporting the boiler, comprising a plurality of geared rollers, each interposed between an upper and a lower roller seat, and a frame for holding the rollers in spaced relation, and 30 causing them to rotate in unison.

25. In a locomotive, the combination of a plurality of main frames, articulated together; a boiler, rigidly mounted on one of the frames, and extending over another; and means, on said second mentioned frame, for supporting the boiler, comprising means for permitting swivelling movements of the second mentioned frame, relatively to the boiler, embodying a plurality of rollers, each composed of a plurality of separate cylindrical 40 units, each unit being adapted to rotate independently of the others.

35. In a locomotive, the combination of a plurality of main frames, articulated together; a boiler, rigidly mounted on one of the frames, and extending over another; and means, on said second mentioned frame, for supporting the boiler, comprising means for permitting swivelling movements of the second mentioned frame, relatively to the boiler, embodying a plurality of rollers, each composed of a plurality of separate cylindrical 50 units, each unit being adapted to rotate independently of the others, a guide frame, in which the rollers are mounted, and a swivel yoke, in which the guide frame is fitted.

45. In a locomotive, the combination of a plurality of main frames, articulated together; a boiler, rigidly mounted on one of the frames, and extending over another; and means, on said second mentioned frame, for supporting the boiler, comprising a boiler saddle, a boiler bearing yoke, a swivel yoke, mounted for swivelling movement in said 60 boiler bearing yoke, and a plurality of rollers,

fitted in the swivel yoke, and interposed between the boiler saddle and the boiler bearing yoke.

10. In a locomotive, the combination of a plurality of main frames, articulated together; a boiler, rigidly mounted on one of the frames and extending over another; and means, on said second mentioned frame, for supporting the boiler, comprising a boiler saddle, a boiler bearing yoke, four thrust 70 blocks mounted in said yoke, a swivel yoke, having two arms extending transversely of the second mentioned frame, and two arms extending longitudinally thereof, each of said arms being adapted to transmit thrust 75 to one of said thrust blocks, and a plurality of rollers, mounted in said swivel yoke, and interposed between the boiler saddle and the boiler bearing yoke.

15. In a locomotive, the combination of a plurality of main frames, articulated together; a boiler, rigidly mounted on one of the frames, and extending over another; and means, on said second mentioned frame, for supporting the boiler, comprising a boiler 80 bearing yoke, a swivel yoke, mounted on the boiler bearing yoke, a roller guide, mounted in the swivel yoke, rollers, mounted in the guide, a crosshead, bolted to the boiler bearing yoke, and slidably fitted in the roller 85 guide, and a boiler saddle mounted on the rollers.

20. In a locomotive, the combination of a plurality of main frames, articulated together; a boiler, rigidly mounted on one of the frames, and extending over another; and means, on said second mentioned frame, for supporting the boiler, comprising a boiler 90 bearing yoke, a swivel yoke, mounted on the boiler bearing yoke, a roller guide, mounted in the swivel yoke, a pair of pins, mounted in the guides, a roller, composed of a plurality of narrow cylindrical units, rotatively mounted on each pin, a boiler saddle, mounted on the rollers, a bevel gear, mounted on the outer end of each pin, an upper rack, attached to the boiler saddle, and a lower rack, attached to the boiler bearing yoke, for each bevel gear, and means, depending from the boiler saddle and slidably fitted in the swivel 95 yoke, for transmitting lateral thrusts of the boiler to the swivel yoke.

25. In a locomotive, the combination of a plurality of main frames, articulated together; a boiler, rigidly mounted on one of the frames, and extending over another; and means, on the second mentioned frame, for supporting the boiler, comprising a bed plate, a boiler bearing yoke, mounted above the bed plate, a swivel yoke mounted above the boiler bearing yoke, a boiler saddle, mounted above the swivel yoke, lower roller seats, formed with racks, mounted on the bed plate, upper roller seats, formed with racks, mounted on the boiler bearing yoke, rollers, interposed 100

between the seats, having gear teeth meshing with the racks thereof, and rollers, fitted in the swivel yoke, and interposed between the boiler saddle and the boiler bearing yoke.

5 14. In a locomotive, the combination of a plurality of main frames, articulated together; a boiler, rigidly mounted on one of the frames, and extending over another; and means, on the second mentioned frame for supporting the boiler, comprising a bed plate,

a boiler bearing yoke, a swivel yoke, a boiler saddle, a geared roller lateral motion device, interposed between the bed plate and the boiler bearing saddle, and rollers, fitted in the swivel yoke and interposed between the boiler saddle and the boiler bearing yoke, for facilitating swivelling movements of the second mentioned frame relatively to the boiler. ¹⁵
